Inventor

Louis Roth,

By J. Richard Paris.

Attorney

UNITED STATES PATENT OFFICE.

LOUIS ROTH, OF BALTIMORE, MARYLAND.

SHOE.

Application filed March 12, 1925. Serial No. 15,055.

To all whom it may concern:

Be it known that I, LOUIS ROTH, a citizen of the United States, residing at Baltimore, in the county of Baltimore and State of Maryland, have invented a new and useful Improvement in Shoes, of which the following is a specification.

This invention relates generally to the construction and manner of manufacture of 10 shoes, slippers, sandals, comforts, and other footwear. It relates more specifically to the manner of attaching the upper of the shoe, sandal or the like to the sole and to the product resulting therefrom. The sole of 15 the shoe or the like may be of leather, rubber, or of any of the materials or compositions commonly used for such purposes. The upper may be made of leather, of cloth or of any other material commonly used 20 for such purposes. The upper may or may not be provided with a lining.

It is the object of this invention to provide a shoe or sandal in which the stitches, which pass through the upper of the shoe 25 and the sole of the shoe for the purpose of attaching the one to the other, are not exposed on the wearing face of the sole and do not pass through the wearing face of the sole.

Another object of this invention is to provide a shoe or sandal or the like in which no part of the material which constitutes 30 the upper of the shoe lies flat against the inner face of the sole of the shoe.

A further object of the invention is to provide a shoe which is easy and cheap to manufacture and which has a neat and ornamental appearance.

The above objects are accomplished by 40 providing the sole of the shoe with an up-standing flange extending around all of the outer edge of the upper face of the sole, and sewing the upper on to the inner face of said flange. The flange may be integral 45 with the sole or it may consist of a separate strip of material which is sewed on to the upper face of the sole. The sole may be pressed, shaped or molded in such a manner as to produce the integral flange; or the flange may be obtained by any other 50 process known in the art. The flange preferably extends upwardly from the inner face of the sole to a height substantially equal to the thickness of the sole.

If the flange is made of a separate piece 55 of material it may be made of the same material as the sole or it may be made of any material desired. The separate flange may be attached to the sole by stitching or 60 in any other manner desired.

In the drawings which constitute a part 65 of this specification

Fig. 1 is a view of a shoe constructed in the manner disclosed herein and in accordance with this invention.

Fig. 2 is a sectional view along the line 2—2 of Fig. 1.

Fig. 3 is a view similar to Fig. 2 of a modified form of the invention.

Fig. 4 is a view similar to Fig. 2 of another modified form of the invention.

Fig. 5 is a view similar to Fig. 2 of a still further modified form of the invention.

In the drawings 10 is the upper of the 75 shoe and 11 is the sole of the shoe. In the modification shown in Fig. 2 the sole is so shaped, pressed or molded that the flange 12 is integral with the sole of the shoe and constitutes a part thereof. The upper 10 which may or may not be provided with a lining 13 abuts flush against the inner face 14 of the sole and is sewed on to the flange 12 by means of the stitches 15 in the manner shown. The stitches do not pass 80 through the wearing face of the sole and pass in a direction parallel to the face of the sole. The stitching should preferably be disposed near the upper edge of the flange. As a result the shoe has no part of 85 the upper lying flat against the inner face of the sole. The shoe presents only the flat inner surface of the sole to the foot of the wearer, and, if desired, the use of an inner sole may be dispensed with.

In the modification illustrated in Fig. 3 the lower edge of the upper is turned outwardly and back upon itself, thus affording a strip 17 which is stitched on to the flange 18 of the sole 19 by means of the stitches 20. When the shoe is finished the upper 16 is pressed against the strip 17 and substantially hides it from view with the result that the shoe presents a very neat and finished appearance.

The soles 11 and 19 may be made of any moldable composition such as rubber or the like and the soles may have been molded

to the desired shape. The soles may also be made of leather and pressed or otherwise given the desired shape.

In the modification illustrated in Fig. 4 the sole 21 is flat and has a separate strip 22 attached to it all around the outer edge of the upper face. The upper 23 is attached to the strip 22 on its inner face by means of stitching 24, and the strip 22 is attached to the sole 21 by means of stitching 25. The strip 22 may be of leather and may be attached to the sole 21 in the manner shown. If desired the sole 21 and the strip 22 may be made of rubber, in which case the strip 22 may be vulcanized on to the sole 21 and the stitches 25 omitted.

Fig. 5 shows the strip 22 replaced by an ornamental cord 26. The construction of the shoe is otherwise the same as that shown in Fig. 4. In each of these figures the upper may if desired be attached to the strip in the manner shown in Fig. 3. It is also obvious that the upper may be attached to the strip either before or after the strip has been attached to the sole.

All modifications are alike in their substantial and important respects. The soles 11, 19, and 21 are in each case provided with a flange 12, 18, 22, or 26 as the case may be. The lower edge of the uppers 10, 16 or 23 in each form abuts against the inner face of the sole, and the lower peripheral portion of the upper in each form lies flat against the inner face of the flange and is attached to said flange by means of stitches which are disposed in a plane substantially parallel to the plane of the sole.

Having described my invention, I now claim:

40 1. A shoe comprising a flat sole, a flange

along the outer edge of the sole extending upwardly from the inner face of the sole to a height substantially equal to the thickness of the sole, an upper, and stitches passing through the lower peripheral portion of the upper and through the flange, said stitches being disposed in a plane substantially parallel to the plane of the sole, whereby the upper is attached to the sole, the marginal edge of the upper abutting against the inner flat face of the sole.

2. A shoe comprising a flat sole, a strip of material attached to the outer edge of the sole and constituting a flange extending upwardly from the inner face of the sole to a height substantially equal to the thickness of the sole, an upper, and stitches passing through the lower peripheral portion of the upper and the strip, said stitches being disposed in a plane substantially parallel to the plane of the sole, whereby the upper is attached to the sole, the marginal edge of the upper abutting against the inner flat face of the sole.

3. In the process of manufacturing shoes, the steps of forming an upstanding flange extending upwardly from the inner face of the sole to a height substantially equal to the thickness of the sole along the peripheral edge of a flat sole, disposing the upper with its lower marginal edge abutting the inner flat face of the sole, and attaching the lower peripheral portion of the upper to the inner face of the flange by stitches passing in a plane substantially parallel to the plane of the sole.

In testimony whereof I hereunto affix my signature.

LOUIS ROTH.
